UNITED STATES PATENT OFFICE.

CHARLES G. QUACKENBUSH, OF TOLEDO, OHIO.

BOOKCASE.

1,072,258.

Specification of Letters Patent.

Patented Sept. 2, 1913.

Application filed January 22, 1913. Serial No. 743,564.

To all whom it may concern:

Be it known that I, CHARLES G. QUACKENBUSH, a citizen of the United States, residing at Toledo, in the county of Lucas and State 5 of Ohio, have invented new and useful Improvements in Bookcases, of which the following is a specification.

This invention relates to improvements in knock down sectional book cases and other 10 analogous structures and consists in the construction, combination and arrangement of devices hereinafter described and claimed.

One object of the invention is to effect improvements in the construction of the walls 15 and back of the case or other structure, whereby the said parts are adapted to be readily detached or assembled, without the necessity of employing implements or tools of any kind, and whereby the back is utilized 20 for locking the other parts of the structure together.

Another object of the invention is to provide improved means for hanging the door of the case so as to permit the door to be 25 swung to either an open or a closed position and to also permit the door to be run in out of the way under the top or upper wall of the case, the door hanging means being disposed entirely out of the way and being so 30 arranged and constructed as to prevent the door from binding.

In the accompanying drawings:—Figure 1 is a vertical longitudinal sectional view of one end portion of a knock down sectional 35 book case constructed in accordance with my invention. Fig. 2 is a horizontal sectional view of the same on the plane indicated by the line *a—a* of Fig. 1. Fig. 3 is a vertical transverse sectional view of the same on the 40 plane indicated by the line *b—b* of Fig. 1, showing the door in vertical, closed position. Fig. 4 is a similar view of the same on the plane indicated by the line *c—c* of Fig. 1, showing the door in open elevated position 45 in full lines and run in, out of the way, under the top wall or shelf of the case in dotted lines.

For the purposes of this specification, the bottom shelf, wall or member of the book 50 case or other analogous structure is shown at 1, the top wall or shelf at 2, one of the end walls at 3 and the back at 4.

The end wall is provided in its upper and 55 lower edges with grooves 5. These grooves are arranged in pairs, extend longitudinally of the end wall, that is to say, from its front

to its rear sides thereof, and are inclined and arranged in converging relation. The bottom and top walls or members of the case are provided, respectively, on their upper and 60 lower sides, near their ends, with locking channel plates 6 which have converging walls 7 to engage the said grooves 5. These channel plates are secured to the bottom and top members of the case by screws or other 65 suitable means and their inclined walls contact with the grooves of the end members to detachably secure the top, bottom and end members together and prevent them from being separated excepting by sliding the top 70 and bottom members longitudinally of the said end members, as will be understood.

The grooves 5 and the locking channel plates terminate short of the front sides of the top, bottom and end members so that 75 they are spaced from the front of the case. The said locking channel plates also terminate short of the rear sides of said case members. The top and bottom members of the case are recessed on their rear sides as at 80 8 and the end members are provided on their opposing sides, near their rear edges, with vertical grooves 9 which are coincident with the recessed portions of the top and bottom members and which serve to receive the ends 85 of the back 4. The back when in place in the said end grooves bears against the rear sides of the top and bottom members, and, hence, locks the latter to the end members against sliding movement thus preventing the case 90 from being disassembled until after the back has been removed. To hold the back in place and against sliding in the grooves, the top and bottom members of the case are provided with headed studs 12 which project 95 therefrom and engage notches in the upper and lower sides of the back.

The top wall or member 2 of the case is provided on its under side, at points near its ends, with transverse grooves 13 which 100 extend from its rear side nearly to but short of its front side or edge. Guiding and supporting bars 14 are arranged in these grooves each having its front end secured to the under side of the top wall as at 15 105 and its rear end upturned and secured to the rear side of the top wall as at 16. These guiding and supporting bars are of less cross sectional dimensions than the grooves and are arranged centrally with respect to 110 the grooves so that they are out of contact with the sides of the grooves and so that

their lower sides are in a common plane with the lower surface of the top member or wall.

The door 17 may be of any suitable construction and is provided at its upper side, near its ends, with hinges 18 each of which comprises a leaf 19 which is secured directly to the upper edge or side of the door and a leaf 20 pivotally connected to the leaf 19 and which forms a slide or hanger member. The slides or hanger members are arranged under the guiding and supporting bars for sliding movement with respect thereto and are provided on their upper sides with peripherally grooved rollers 21 which are mounted on axle studs 22 with which the slides are provided. These peripherally grooved rollers extend into the grooves of the top wall or member 2 of the case and their grooved peripheries engage opposite side edges of the guiding and supporting bars so that the slides are connected to the guiding and supporting bars for longitudinal movement.

25 The hinges permit the door to be turned to a closed vertical position or raised to a horizontal open position and also permit the door after it has been raised to a horizontal position, to be run in, out of the way, under the top wall, shelf, or member 2 of the case by reason of the sliding connection between the slide members of the hinges and the guiding and supporting bars, as will be understood.

30 35 The end walls of the case are provided on their opposing sides near their front edges, with guiding and supporting and stop rollers 23 which may be made of rubber or any other suitable material and are mounted for rotation on suitable axle studs 24. These rollers 23 bear under the lower side of the door and support the latter when in raised and retracted position and are spaced a sufficient distance from the front edges of the 40 45 end walls of the case to permit the door after it has been moved forwardly to its

full extent, to be turned down to closed vertical position in the front side of the case.

The rear ends of the grooves in the top member of the case are open, and the upturned rear ends of the guiding and supporting bars are provided with notches 25 in their sides to clear the rollers on the slide members of the hinges and, hence, after the top, bottom and end members of the case have been detached from one another, the door may be readily and entirely disconnected from the top member by merely pushing the latter rearwardly so as to cause the rollers of the slides to entirely disengage the guiding and supporting bars.

While I have herein shown and described a preferred form of my invention, I would have it understood that changes may be made in the form, proportion and construction of the several parts without departing from the spirit of the invention and within the scope of the appended claim.

I claim:—

In a structure of the class described, a wall having a transverse groove in one side closed at its front end and open at its rear end, a guiding and supporting bar arranged longitudinally of the groove, spaced from the sides thereof and secured at its ends to said wall, that portion of the said bar which is secured to the rear side of the wall being upturned and notched, a slide on the outer side of the bar having means to slidably secure the same to the bar, said securing means extending into and being cleared by the groove and being also cleared by the notched upturned rear portion of the supporting bar when the slide is at the rear end of the groove, and a door pivotally connected to and movable with the slide.

In testimony whereof I affix my signature in presence of two witnesses.

CHARLES G. QUACKENBUSH.
